Assistant Examiner — Altaira J Swangin

(57) **CLAIM**

The ornamental design for a base for an interchangeable barrel hair curling iron, as shown, and described.

DESCRIPTION

FIG. 1 is a top, front, left perspective view of a base for an interchangeable barrel hair curling iron;

FIG. 2 is a front view thereof;

FIG. 3 is a rear view thereof;

FIG. 4 is a left side view thereof;

FIG. 5 is a top view thereof;

FIG. 6 is a top perspective view thereof;

FIG. 7 is a bottom view thereof;

FIG. 8 is another top, front, left perspective view thereof in a use environment;

FIG. 9 is a top, front, left perspective view of a base for an interchangeable barrel hair curling iron of FIG. 1 shown in a second position thereof;

FIG. 10 is a left side view thereof;

FIG. 11 is a right side view thereof;

FIG. 12 is a front view thereof;

FIG. 13 is a top view thereof;

FIG. 14 is a top, front perspective view thereof;

FIG. 15 is a bottom view thereof; and,

FIG. 16 is another top, front, left perspective view thereof in a use environment.

The broken lines in FIGS. 8 and 16 depict environment subject matter and in FIGS. 7 and 15 depict structure of the article that form no part of the claimed design. None of the broken lines form part of the claimed design.

1 Claim, 16 Drawing Sheets
